H. WAYWELL,
WINDOW CLEANING DEVICE,
APPLICATION FILED JULY 24, 1919.

Patented Nov. 16, 1920.

Inventor,
Harry Waywell

By John A. Brumhart

Atty.

UNITED STATES PATENT OFFICE.

HARRY WAYWELL, OF CLEVELAND, OHIO.

WINDOW-CLEANING DEVICE.

1,358,804.

Specification of Letters Patent. Patented Nov. 16, 1920.

Application filed July 24, 1919. Serial No. 318,664.

To all whom it may concern:

Be it known that I, HARRY WAYWELL, a subject of Great Britain, residing at Cleveland, in the county of Cuyahoga and State 5 of Ohio, have invented certain new and useful Improvements in Window-Cleaning Devices, of which the following is a specification.

This invention relates to a window cleaning device for removing rain, snow or moisture from the vestibule windows of electric cars but may with slight changes be used on wind shields of automobiles or in any similar place where it is essential that the view be 15 unobstructed especially in wet or stormy weather.

The object of the device is in the provision of means which will enable the wipers to be easily moved upon the surface of the glass, 20 the construction of said means being such as to form a perfect contact between the wipers and the glass at all times.

With the foregoing objects in view the invention consists in certain elements particularly pointed out in the accompanying drawings in which like reference numerals designate similar parts of reference throughout the various views, and in which Figure 1 is a front elevation of the device secured in 25 its proper relation to the window of an electric car; Fig. 2 is a central vertical section through the device; Figs. 3, 4 and 6 are sectional details on corresponding lines of Fig. 2 and Fig. 5 is a rear elevation of the upper 35 end of one of the wipers.

The device itself consists of two parallel arms 3 and 4 which are substantially U-shaped in cross section, the upper portion of the arms being widened as shown at 5 to permit 40 of providing a squared opening 6 into which is fitted the squared ends 7 of the tubular bearing 8 which passes through an enlarged bore 9 in the sash, washers 10 and 11 being so positioned in the bore as to provide a 45 bearing surface for the tube 8, the two arms are retained in place by passing a round head bolt 12 through the tube 8, said bolt having applied to its reduced threaded end a wing nut 13 which may be applied up to a 50 shoulder 12^a formed upon the bolt and extending the full length of the tube 8. By this means the associated parts are held in a fixed position relative to each other and provide a bearing which will allow of easy 55 swinging of the arms 3 and 4 about the win-

dow pane and by reason of the squared connection both arms swing at the same time. The arms 3 and 4 have secured thereupon rubber squeegees 14, said squeegees extending from a point near the pivot of the arms 60 to within a short distance of the bottom, said squeegees being firmly held in place by having the metal of which the arms are made firmly pressed about them and projecting approximately one-fourth of an inch beyond 65 the metal thereof toward the glass. This permits of slight yielding movement of the squeegees when the arms are swung about their pivot point presenting thereby the sharp corner of the squeegees to the glass 70 which effectually removes any moisture or the like therefrom.

The aforementioned arms are provided at their free ends with rubber rollers 15 in the form of rings which are so constructed as to 75 permit of easy replacement, these rings being mounted between an annular flange 16 formed about a cup shaped washer 17 and a second washer 18 which assembly is pivotally mounted upon a stud 19 secured to the 80 free end of the wiper arm. These may be secured in any suitable manner, here shown as provided with flattened portions 20 which after being assembled, are retained in place by having the metal of the wiper arms 85 pressed inwardly as shown at 22, this provides a cheap and efficient way of securing the rollers to the wiper arms, while the rollers hold the arms in proper relation to the glass. An operating handle 23, consisting of 90 a wooden ball mounted upon a stud 24 which may be secured in the wiper arms 3 in a manner similar to that described for the studs 19 provides an easy means for normally operating the same by the user. 91

I claim:

A window cleaner comprising an arm U-shaped in cross-section to provide opposite flanges, and provided with a wiper strip held between said flanges, a stud clamped between 10 said flanges at the end of the arm, and a spacing roller rotatably mounted upon said stud.

In testimony whereof I do affix my signature in presence of two witnesses.

HARRY WAYWELL.

Witnesses:

JOHN A. BOMMHARDT,
ROBERT L. BRUCK.
